Inventor

JOHN G. WELLING

Attorney

UNITED STATES PATENT OFFICE.

JOHN G. WELLING, OF CINCINNATI, OHIO.

CIRCUIT-BREAKER LOCK.

Application filed February 21, 1922. Serial No. 538,399.

To all whom it may concern:

Be it known that I, JOHN G. WELLING, a citizen of the United States of America, and a resident of Cincinnati, in the county of 5 Hamilton and State of Ohio, have invented a new and useful Improvement in a Circuit-Breaker Lock, of which the following is a specification.

My invention relates to locks and more 10 particularly locks for electrical circuits and the like on automobiles, and has for an object the provision of an improved and novel form of lock adapted for use on automobiles and the like for cutting out circuits.

Another object of my invention is to provide a device of this type wherin an effective and positive electrical connection is attained.

These and other objects are obtained by 20 means described herein and disclosed in the accompanying drawings, in which:

Fig. 1 is a longitudinal sectional view of a device embodying my invention.

Fig. 2 is an end view of a device shown in 25 Fig. 1, the cap being removed.

Fig. 3 is a sectional view on line 3—3 of Fig. 2.

Fig. 4 is a view of a key such as may be employed with my device.

My invention comprises a casing 4 having fixedly mounted within it spaced contacts 17 which may be brought into positive electrical connection with one another by means of a reciprocating block 18 carrying conductors 30 19 adapted to engage various of the contacts.

The casing 4 has an enlarged front end or head and a reduced tail or rear end. The casing is preferably cylindrical in form, the enlarged and reduced portions thereof being substantially concentric. The casing has an axial bore 5 which is considerably larger in the head of the casing than in the reduced portion thereof. The head of the casing 40 carries a radially extending flange 6 which serves as a seat for a flange 7 mounted on a cap 8 adapted to close the forward end of the casing. The cap is secured on the casing in any suitable manner such as by means of rivets 9. The cap has formed in its slots 45 10 through which the wires 11 may enter

the casing. The casing at its forward end is internally screw threaded as shown at 12, and has a shoulder 13 formed at the forward end of such screw threaded portion. A fixed 55 insulator block 14 is mounted upon the threaded portion of the casing and has a flange 16 which lies upon the shoulder 13. Contact posts 17 extend through the block 14 and each has its forward end electrically 60 connected with a wire 11. A reciprocating insulator block 18 is contained within the enlarged bore in the casing, and carries conductor bars 19 upon that face immediately adjacent the fixed insulator block. The conductor bars are secured upon the reciprocating block in any suitable manner such as by means of the screws 20, and each conductor bar is adapted to effect positive electrical connection between the inner ends of 70 two of the contact posts. A composition of lead and solder is mounted over the heads of the screws 20 and provides a contact face for the inner ends of the contact posts. The rear face of the reciprocating block 18 has 75 an axial threaded bore 21 into which the threaded head 22 formed on a rod 23 engages. A flange 15 is formed on the rod 23 and is seated in the enlarged unthreaded rear end of the bore in the reciprocating 80 block. Set screw 24, extending through the flange 15 and engaging in the block 18, precludes relative rotatory motion of the block 18 and the rod 23. The reduced portion of the casing is developed into a series 85 of concentric steps 25, 26 and 27. The portion 26 is screw threaded and has mounted upon it, the threaded end of a thimble 28 the forward end of which abuts against a shoulder 29 formed at the junction of the 90 steps 25 and 26. The rear-most end of the bore in the reduced portion of the casing is developed into an angular form, for example square in cross section, as shown in Fig. 1, and through which the angular or 95 square end 30 of the rod 23 may be reciprocated longitudinally of itself. An internal shoulder 31 is formed in the reduced portion of the casing as substantially the forward 100 end of the angular portion of the bore therein. A spring 48 is disposed about the rod 23 and its ends abut the shoulder 31 on

the casing and the flange on the rod 23. The step 27 has formed on its exterior surface, coarse threads 32, which are engaged by the internal threads formed on a nut 33 5 reciprocally contained within the thimble 28 and having an axial bore 34, intermediate the ends of which bore is formed a seat 35 upon which the head 36 of a screw 37 slidably engages. The threaded shank 38 of the 10 screw engages in a threaded axial bore 39 in the angular end of the rod 23. Lugs 40 extend from the rear end of the nut 33 whereby the nut may be rotated by means of a suitable key 45 which may be inserted 15 between the lugs 40. The rear face 41 of the thimble is ordinarily mounted on the dash 42 of an automobile and has a suitable slot 43 formed in it through which the key may be inserted. A lug 44 extends from the 20 rear face of the thimble and serves as a stop for the key. The complementary threads formed on the rod 23 and the nut 33 are of such pitch that the movement of the nut through an arc of about 120 degrees will 25 cause the rod 23 to be reciprocated longitudinally of itself or approximately $\frac{1}{8}$ of an inch, and the movement of the key thru the remaining 220 degrees before it engages the stop, permits the rod 23 to be solely 30 under the influence of the spring 48.

The operation of my device is as follows:

When the parts are in the relation shown in Figs. 1 and 3, an electrical contact is 35 made between the posts 46 and 47 through a conductor bar 19. It is desirable that in installing my device that both the positive and negative wires from the battery pass through the lock, one of the wires can be grounded beyond the lock, thereby not in 40 any way effecting the ordinary wiring of any type of automobile. When the key is inserted between the lugs 40 on the nut, and the nut is revolubly actuated thereby, the rod 23 is reciprocated longitudinally of itself, such movement being determined by 45 the direction of movement of the key. This longitudinal movement is effected by virtue of the casing and thimble being stationary. The nut 33 is the only element capable of 50 rotatory motion. When such motion is imparted to the nut, the nut moves longitudinally of the casing and thimble, and as the screw 36 secures the rod 23 upon the nut, the longitudinal movement of the nut is imparted to the rod 23, thereby moving the 55 conductor bars 19 either toward or away from the posts 17. The spring 48 is at all times under a very high degree of compression and when the conductor bars are actuated longitudinally of themselves so as to be 60 solely under the influence of the spring, the compressional force of the spring effects a positive and firm contact of the conductor bars upon the posts which contact is not effected either by the load passing through 65

such conductor or by the vibration of the vehicle, the engagement being so firm that there is no wear on the parts of the device.

What I claim is:

1. In a device of the class described the 70 combination of a casing having a bore therein, one end of the bore being angular, a fixed insulating block in the bore, contact posts on the block having electrical connectors extending from the casing, a reciprocating insulating block in the bore, conductor bars on the reciprocating block adapted to electrically connect the contact posts, a rod mounted at one of its ends on the reciprocating block slidable longitudinally of itself in the bore, a shoulder on the casing extending into the bore, a spring the 75 ends of which abut the shoulder and the reciprocating block, an angular head on the other end of the rod engaging reciprocally in the angular bore in the casing, screw threads formed on the casing at the end having the angular bore, a threaded nut adapted to engage the threads on the casing, and a connection between the nut and the 80 rod adapted to permit relative rotatory motion of the nut and the rod and to transmit longitudinal movement of the nut to the rod.

2. In a device of the class described the 85 combination of a casing having a bore therein, one end of the bore being angular, a fixed insulating block in the bore, contact posts on the block having electrical connectors extending from the casing, a reciprocating insulating block in the bore, conductor bars on the reciprocating block adapted to electrically connect the contact posts, a rod mounted at one of its ends on the reciprocating block slidable longitudinally of itself in the bore, a shoulder on the 90 casing extending into the bore, a spring the ends of which abut the shoulder and the reciprocating block, an angular head on the other end of the rod engaging reciprocally in the angular bore in the casing, screw threads formed on the casing at the end having the angular bore, a threaded nut adapted to engage the threads on the casing, and a connection between the nut and the 95 rod adapted to permit relative rotatory motion of the nut and the rod and to transmit longitudinal movement of the nut to the rod.

3. In a device of the class described the 100 combination of a casing having a bore therein, one end of the bore being angular, a fixed insulating block in the bore, contact posts on the block having electrical connectors extending from the casing, a reciprocating insulating block in the bore, conductor bars on the reciprocating block adapted to electrically connect the contact 105 posts, a rod mounted at one of its ends on the reciprocating block slidable longitudinally of itself in the bore, a shoulder on the casing extending into the bore, a spring the 110 ends of which abut the shoulder and the reciprocating block, an angular head on the other end of the rod engaging reciprocally in the angular bore in the casing, screw threads formed on the casing at the end having the angular bore, a threaded nut adapted to engage the threads on the casing, a connection between the nut and the 115 rod adapted to permit relative rotatory motion of the nut and the rod and to transmit longitudinal movement of the nut to the rod, and a slotted thimble mounted on the casing and enclosing the nut, the slot in the thimble 120 permitting ready access to the nut for rotation thereof.

3. In a device of the class described the 125 combination of a casing having a bore therein, one end of the bore being angular, a fixed insulating block in the bore, contact posts on the block having electrical connectors extending from the casing, a reciprocating insulating block in the bore, conductor bars on the reciprocating block adapted to electrically connect the contact 130

posts, a rod mounted at one of its ends on the reciprocating block slideable longitudinally of itself in the bore, a shoulder on the casing extending into the bore, a spring the ends of which abut the shoulder and the reciprocating block, an angular head on the other end of the rod engaging reciprocally in the angular bore in the casing, and rotatable means for reciprocating the angular head in its bore. In testimony whereof, I have hereunto subscribed my name this 14th day of February, 1922.

JOHN G. WELLING.
